UNITED STATES PATENT OFFICE.

EDWIN INGRAM, OF PHILADELPHIA, PENNSYLVANIA, ASSIGNOR TO THE NATIONAL AUTOMATIC CAR COUPLER COMPANY, OF NEW JERSEY.

CAR-COUPLING.

SPECIFICATION forming part of Letters Patent No. 286,444, dated October 9, 1883.

Application filed July 6, 1883. (No model.)

To all whom it may concern:

Be it known that I, EDWIN INGRAM, of Philadelphia, in the county of Philadelphia and State of Pennsylvania, have invented certain Improvements in Car-Couplings, of which 5 the following is a specification.

This invention relates to that class of car-couplings wherein a vertically-swinging link connected to one of the draw-heads is designed 10 to engage by a downwardly-swinging movement with the opposite draw-head, and is designed more particularly as an improvement upon the coupling represented in the patent to E. Webber, January 9, 1883, No. 270,523.

15 The aim of the present invention is to render the device more simple and efficient in its action, and to permit the use in an ordinary manner of an elongated link in place of the expensive device represented in the original 20 patent.

Referring to the accompanying drawings, Figure 1 represents a side elevation of my improved draw-head and coupling. Fig. 2 is a top plan view of the same. Fig. 3 is an end elevation of the same looking toward its mouth or end. Fig. 4 is a plan view of the link.

A A represent the two draw-heads, constructed in essentially the same form and manner as those described in the prior patent, each with 30 cavities or chambers *a* in its front face to receive the ordinary coupling-pin, whereby the head may be united to cars fitted with the ordinary appliances. The head is surmounted at the front by a raised portion, C, over and 35 around which the end of the link is engaged, and by means of which the car is drawn. In rear of this horn the head is recessed in the upper side, as shown at D, to admit the end of the link, which is confined therein by means 40 of a longitudinal slide, b, seated in a groove in the upper face of the head, as shown. This slide is designed to be thrown forward by the impact or concussion produced when the cars are brought together for the purpose of actuating the link and moving the same forward 45 that it may engage with the opposite draw-head, its action in this regard being similar to that in the original patent. In place, however, of employing the peculiarly-formed link 50 and the stud on the under side of the slide to

act upon said link, I now employ a link of an elongated form with circular ends, as shown in Fig. 4, and provide the slide with laterally-extending arms *e*, the extremities of which are bent forward, this arm being adapted to 55 engage behind the link to support the same in an inclined position, and to throw the same forward as the heads are brought together. This action will be more clearly understood on reference to the link represented in dotted 60 lines on the right hand of Fig. 1. The lower end of the link is seated in the recess in the top of the draw-head, and the end of the slide passed through it to retain it in position. The slide being moved backward until it bears 65 against a stop-shoulder, E, formed on the draw-head, the link is turned upward and backward past the perpendicular and supported against the forward face of the arm *e*, as shown. Being thus sustained, the concussion produced 70 by bringing the two cars together causes the slide to be thrown forward, whereupon its arms *e*, acting against the rear face of the link, throw the same forward past the perpendicular, whereupon it falls into the position represented in Fig. 1, its free end engaging over 75 and around the horn in the opposite draw-head. The forward extension of the arms *e* enables the same to engage past the sides of the link, in order to maintain the same in an 80 upright position and to prevent it from falling laterally. As an additional means of maintaining the link in its elevated position, I prefer to flatten the outer ends of the same, as represented in Fig. 4, a single flat surface, or two 85 flat surfaces beveled in opposite directions, being employed, as preferred.

In constructing the links I prefer to make the same of such width that when not required for action they may be dropped downward 90 around and past the head, as represented in the right hand of Fig. 1, so as to hang below the same. The link is also constructed of such form and size as to admit of its being turned end for end in the head to which it is attached, 95 so that it may be placed, as shown, crosswise of the head.

In constructing the head I prefer to provide the same on each side with a lug or projection, *i*, against the forward ends of which the link 100

may bear when it is in its pendent position. By thus sustaining the link so that it cannot swing to and fro, the constant weaving action which would otherwise take place is prevented.

5 At its upper surface the horn of the draw-head may be provided with a gravitating latch in substantially the same manner and for the same purpose as the latch represented in the original patent.

10 The lugs *i* maintain the link in such position that when out of action it is prevented from swinging to and fro and being needlessly worn and weakened, as would otherwise occur. The construction of the link so that it 15 may be placed transversely of the head is advantageous in that it facilitates what is commonly known in the art as "making a flying switch."

19 The present invention is restricted to those 20 matters and things which are hereinafter described, and as to all matters which may be described or shown, but which are not claimed, the right is reserved to make the same the subject of a separate application.

25 I am aware that oblong links have been used for coupling cars in connection with coupling-pins, and also with heads in which the links stand vertically or on edge when in action. My improvement consists in the combination of a 30 link of this peculiar form with a draw-head of the special form herein shown, the link swinging downward into engagement and lying when in action in a horizontal position.

Having thus described my invention, what I claim is—

35 1. In combination with the draw-head and link, the slide having laterally-extended arms *e*, to engage behind the link for the purpose of supporting the same and of throwing or tipping the same forward.

40 2. In combination with the draw-head and link, the longitudinal slide mounted upon said draw-head, and provided with laterally-extending arms, the extremities of which are extended forward, as described, whereby they 45 are adapted to prevent the link from falling laterally.

49 3. In an automatic coupling, the combination, with two draw-heads having upright horns on their upper sides, as described, of an oblong coupling-link adapted to engage and disengage the horns by a vertical motion, and to be extended either longitudinally or transversely with respect to the heads, as described 50 and shown.

55 4. The draw-head provided with a top horn or shoulder to receive the link, and with lateral shoulders or studs adapted to hold the link when out of action in an inclined position, whereby the link is prevented from swinging 60 and weaving.

EDWIN INGRAM.
